UNITED STATES PATENT OFFICE.

CHARLES BERNHARD, OF NEW YORK, N.Y.

SLED-PROPELLER.

SPECIFICATION forming part of Letters Patent No. 295,719, dated March 25, 1884.

Application filed January 7, 1884. (No model.)

To all whom it may concern:

Be it known that I, CHARLES BERNHARD, a citizen of the United States, residing at New York, in the county and State of New York, have invented new and useful Improvements 5 in Sleds, of which the following is a specification.

This invention relates to certain improvements in mechanism for propelling and for 10 steering sleds, said improvements being pointed out in the following specification and illustrated in the accompanying drawings, in which—

Figure 1 represents a side elevation. Fig. 15 2 is an inverted plan. Fig. 3 is a plan or top view on a smaller scale than the previous figures. Fig. 4 is a face view of one of the propeller-wheels.

Similar letters indicate corresponding parts. 20 In the drawings, the letter A designates a frame which rests upon the runners B B, and which supports the seat C. The uprights a of the frame form the bearings for a shaft, b, on the outer ends of which are firmly mounted 25 cog-wheels c, which gear in cog-wheels d, mounted loosely on studs e, which are firmly secured in the uprights a and project outward. On the outer end of each of the studs is loosely mounted a hand-lever, D, which carries a 30 pawl, f, that engages with a click or ratchet wheel, g, firmly secured to the appropriate cog-wheel d. By the action of the levers D, therefore, an intermittent rotary motion can be imparted to the cog-wheels d, and through 35 these cog-wheels and cog-wheels c to the shaft b. From this shaft extend two arms, E, which are situated close to the inner surfaces of the uprights a, and are mounted loosely on the shaft b, so that they can swing thereon.

40 From each of the arms E projects a stud, h, which forms the bearing for the propeller-wheel F. These propeller-wheels are mounted loosely on their studs, and in the example shown in the drawings they consist each of 45 two toothed rims with an intermediate hub.

On the shaft b are firmly mounted two pulleys, i, which connect by belts or chains j with the hubs of the propeller-wheels. The outer 50 ends of the arms E are attached to springs k, Fig. 1, which have a tendency to raise the

arms, so as to keep the propeller-wheels out of contact with the ground.

In the rear portion of the frame A is mounted a rock-shaft, l, to one end of which is firmly secured a hand-lever, G, which extends up, so that it can be manipulated by the occupant of the seat C. From said rock-shaft extend elastic fingers m, which bear upon studs n, projecting from the arms E, so that when the rock-shaft is turned in the proper direction 55 60 65 70 75 80 85 90 95 100 the arms E are depressed and the propeller-wheels are brought to bear upon the ground. This operation is performed by means of the hand-lever G, and in order to retain the propeller-wheels in their depressed position a movable stop, o, is provided, which is inserted in a hole behind the hand-lever, as shown in Fig. 1, several such holes being provided, so that by changing the position of the hand-lever and of the stop the elastic fingers m can be brought to bear upon the arms E with more or less force, and the propeller-wheels can be kept down upon the ground with the requisite pressure. When the propeller-wheels are depressed, the sled can be propelled by manipulating the hand-levers D, and it will be seen from the foregoing description that said propeller-wheels, being mounted on independent arms and depressed by elastic fingers, can readily accommodate themselves to the surface over which the sled is to be propelled. On the inner faces of the propeller-wheels are secured blades r, Fig. 4, which assist in propelling the sled when the same moves in snow.

On the front part of the frame A are mounted 85 foot-levers H, and on the rear end of the frame are pivoted the steering-bars I, which connect by ropes or chains with the foot-levers H. If one of these levers is pressed outward, the corresponding steering-bar is brought to bear upon the ground, and the direction in which the sled moves is changed. By depressing both steering-bars at the same time, the motion of the sled can be arrested. The seat C is adjustable on the frame A, so that it can be 90 brought closer to or farther from the foot-levers H, according to the stature of the person occupying the seat. The hand-levers D can be operated in opposite directions, one being drawn back while the other is drawn forward; 95 100

or they can be operated in one and the same direction, both being drawn back simultaneously; and in order to enable the occupant of the seat to increase the stroke of the hand-levers, the seat C may be made to slide on the frame A in the same manner in which the seats in row-boats are made to slide. The hand-levers D may also be provided each with two pawls acting in opposite directions on the ratchet-wheels, so that each lever produces a continuous revolution of the propeller-wheels.

The seat C may be hinged at its back end and provided with a pin, which moves in a slot in the lever G, so that when the seat is depressed the lever G is moved forward and the propeller-wheels are thrown into action.

What I claim as new, and desire to secure by Letters Patent, is—

1. The combination, substantially as hereinbefore described, with a sled, of the propeller-wheels F, mounted on independent arms E,

means for depressing the propeller-wheels upon the ground, the shaft b, connected to the propeller-wheels by belts or chains, the cog-wheels c, mounted on the shaft b, the cog-wheels d, gearing into the cog-wheels c, and the levers D and pawls f, for imparting a rotary motion to the cog-wheels d.

2. The combination, substantially as hereinbefore described, with a sled, of the propeller-wheels F, mounted on independent arms E, the rock-shaft l, lever G, and elastic fingers m, for depressing the propeller-wheels, and means for imparting to the said propeller-wheels a rotary motion.

In testimony whereof I have hereunto set my hand and seal in the presence of two subscribing witnesses.

CHARLES BERNHARD. [L. s.]
